UNITED STATES PATENT OFFICE.

ARTHUR J. HODGE AND HENRY B. RUGGLES, OF PASADENA, CALIFORNIA, ASSIGNEES
TO AMERICAN PRODUCTS COMPANY, OF ST. LOUIS, MISSOURI.

BARREL-HEAD SEAL.

1,265,656.

Specification of Letters Patent.

Patented May 7, 1918.

Application filed July 1, 1915. Serial No. 37,576.

To all whom it may concern:

Be it known that we, ARTHUR J. HODGE and HENRY B. RUGGLES, citizens of the United States, residing at Pasadena, in the county of Los Angeles and State of California, have invented certain new and useful Improvements in Barrel-Head Seals, of which the following is a specification.

This invention has relation to certain new and useful improvements in barrel head seals and fasteners and is an improvement upon our co-pending barrel head seal applications, Serial Nos. 44,237 filed Aug. 7, 1915, and 44,454 filed Aug. 9, 1915, and is especially adapted, as in the referred to co-pending applications, for securing and sealing in position barrel heads of the type shown in our co-pending applications, Serial Nos. 21,432, filed April 14, 1915, and 24,077, filed April 26, 1915.

The invention has for another object the provision of a form of seal of this character which will be constructed in such manner that it may be readily inserted and secured in position and securely fastened to seal the barrel head with which it is engaged and prevent removal of the barrel head without destruction of the seal.

The invention has for a further object, the provision of a barrel head seal and fastener of the above stated character which will be constructed in such manner that an extension of the body plate of the main seal member may be bent over the remaining portion of said body plate and clamped with the same to conceal and prevent withdrawal of the auxiliary seal member, thereby making it impossible to remove the barrel head after the same has been expanded and securely sealed in position within the receptacle.

The invention has for a still further object, the provision of a barrel head seal of this type which will be composed of the minimum number of parts and which will be constructed in such manner that the extension of the body of the main seal member may be clamped around the forward edge of the remaining or stationary portion of said body plate, after being bent over the same to cover and protect and prevent withdrawal of the auxiliary seal member.

The invention has for still another object, the provision of a barrel head seal and fastener of this character which will be composed of only two parts of simple construc-

tion and which may be readily manufactured in blank form and bent or hammered to the desired shape.

With these and other objects in view, the invention consists in the novel construction, combination and arrangement of parts as will be hereinafter more in detail described, and the asserted novelty specifically pointed out in the claims.

In the accompanying drawings, which clearly and fully illustrate the invention:

Figure 1 is a top plan view of a barrel head secured and sealed in position with our improved barrel head seal,

Fig. 2 is a transverse section through the barrel head and barrel, with the main seal member inserted through the barrel head members,

Fig. 3 is a view similar to Fig. 2, showing the barrel head expanded and the main and auxiliary seal members in operative position,

Fig. 4 is a view similar to Fig. 3, with the extension of the body plate of the main seal member bent back over the main portion of said body plate and clamped over the same to seal the barrel head in position,

Fig. 5 is a plan view of the blank from which the main seal member is constructed,

Fig. 6 is a front elevation of the main seal member in its normal position and removed from the barrel head, and

Fig. 7 is a front elevation of the auxiliary seal member.

Referring more particularly to the drawings, in which similar reference characters designate corresponding parts throughout the several views, 1 designates a portion of a barrel or other receptacle, within the croze 2 of which is positioned the inner head member 3, which is preferably flat and solid and may be formed of any suitable material, as for instance, compressed pulp, fiber or the like, and upon which rests the edge of the outer barrel head member 4, usually of the same material as the member 3, which member 4 is preferably of concavo-convex form and provided with a radial slit 5 extending from the edge of the outer head member 4 to the central opening 7 which is suitably reinforced, as will be readily understood by referring to Figs. 2, 3 and 4 of the drawings. It will also be understood that the reinforced central opening 7 is directly above the reinforced central opening 6 of the in-

- ner head member 3. This construction of the head is clearly and fully described in and covered by our co-pending application, Serial No. 24,077, and does not form a part 5 of the subject matter of this application, but is shown and briefly described in this application so that this form of barrel head seal may be illustrated and described as applied to this type of barrel head.
10. In the present form of barrel head seal, the main seal member is formed from a blank shown in Fig. 5, which has its forward edge 8 bent upwardly and outwardly, as clearly shown in Fig. 8, the front half of 15 the blank forming the horizontal body plate 9 of the main seal member, while the rear half of the blank forms the plate extension 10, which has its free or rear edge bent downwardly and then upwardly to form a 20 pocket 11 to receive the edge 8 and a flange 12 to be bent under said edge 8 after the plate extension 10 is bent back over the horizontal body plate 9 of the main seal member, as will be later clearly and fully 25 understood, and as is shown clearly in Figs. 1 and 4 of the drawings, in which figures the barrel head is shown as being secured and sealed in expanded position within the croze 2 of the receptacle 1.
30. The blank shown in Fig. 5 is provided with a pair of parallel slits 13 which are connected at their rear ends with the oppositely and outwardly directed slits 14 at right angles to the slits 13. The slits 14 also connect at their outer ends with short rearwardly directed slits 15 which have the outer ends of diverging and connected slits 16 connected with their rear ends. The material between the slits 13 and the slits 15, 35 and also between the slits 16 and 14 is bent downwardly along the dotted line 17 to form the shank 18 of the main seal member for insertion through the central openings 7 and 6 of the barrel head members 4 and 3 40 respectively.
45. The shank 18 is also provided with a pair of parallel right angled ears 19 at its lower end by bending the side extensions of the same along the dotted lines 20, in Fig. 5 of 50 the drawings.
55. After the main seal member has been properly placed in position, as shown in Fig. 3 of the drawings, the auxiliary seal member is inserted, as also shown in Fig. 3, and this auxiliary seal member is constructed of a blank of suitable material, which blank is bent back upon itself from its opposite ends, as shown at 21 in Fig. 7, against the under face of the body 22 of said auxiliary seal member. The ends of the blank are then extended downwardly parallel with one another to form the sides 23 of the auxiliary seal member and then bent inwardly and overlapped, as shown at 24 to form the 65 lower end of the depending portion of said

auxiliary seal member, the bottom or lower end of the depending portion of said auxiliary seal member being preferably inclined, as clearly shown in Figs. 3 and 4 of the drawings. The lower end of the auxiliary seal member is also preferably extended at its lower edge, as shown at 25, to automatically force the shank 18 of the main seal member against one wall of the openings 6 and 7 as the auxiliary seal member is forced 75 downwardly through the opening in the body plate 9 of the main seal member formed by striking out or bending down from the latter the shank 18, as previously described. The extension 25 also serves to lock automatically the auxiliary seal member in position after the latter has been forced downwardly to operative position and opposite and pressing against the shank 18 with the extension 25 opposite the extended and 80 slightly bent lower extremity 26 of said shank 18.

By referring to Figs. 3 and 4 of the drawings, it will be seen that after both the main and auxiliary seal members have been placed 90 in proper position with the barrel head expanded and secured in position, the upper or horizontal portion of the auxiliary seal member rests upon the upper face of the body plate of the main seal member and extends only slightly above the same. The plate extension 10 is then bent back over the body plate 9 of the main seal member and over the upper portion of the auxiliary seal member resting upon the same, as clearly 100 shown in Fig. 4 of the drawings, the plate being bent at the transversely curved connecting portion 27 thereof, connecting the extension plate 10 with the body plate 9 and preferably opposite the short slits 15, which 105 slits 15 are clearly illustrated in Fig. 5. The pocket 11 receives the edge 8, as previously described, and a suitable tool is then employed for bending and clamping the flange 12 around and under said edge 8 of the body 110 plate 9, as clearly shown in Fig. 4 and also Fig. 1 of the drawings, thereby securely sealing the head in position and preventing removal of the auxiliary seal member or main seal member from said head without 115 first destroying or injuring the seal to such extent as to leave evidence of the unauthorized party's act.

While the preferred embodiment of the invention has been shown and illustrated, it 120 will be understood that minor changes in the details of construction and arrangement of parts may be resorted to within the scope of the appended claims without departing from the spirit of the invention or 125 sacrificing any of the advantages of the same.

What is claimed is:

1. A barrel head seal and fastener including a main seal member having a body plate 130

and an extension formed with the latter, an auxiliary seal member removably engaged through said body plate and coöperating with the main seal member, said main seal member having a shank depending from said body plate, said extension being adapted to be bent back over said body plate to cover and protect the auxiliary seal member, the edges of said extension and said body plate being adapted to be clamped together, and locking ears carried by the shank of the main seal member.

2. A barrel head seal and fastener comprising a main seal member including a body plate having a shank depending from the same for engagement through a barrel head to expand the latter within a receptacle, an extension plate extending from one edge of said body plate, an auxiliary seal member removably engaged through said body plate adjacent said shank, said extension plate being adapted to be bent back over said body plate and said auxiliary seal member and clamped around the opposite edge of said body plate to prevent withdrawal of said auxiliary seal member, and locking ears carried by said shank.

3. A barrel head seal and fastener comprising a main seal member including a body plate, having one edge bent upwardly

and outwardly, and an extension and sealing plate projecting from the opposite edge of said body plate, and an auxiliary seal member depending through said body plate and having a flattened portion resting upon the latter, said extension plate being adapted to be bent back over said body plate and said auxiliary seal member and clamped around the upwardly and outwardly bent edge of said body plate to prevent movement or withdrawal of said auxiliary seal member.

4. A barrel head seal and fastener comprising the combination with a main seal member having an opening formed therein and a sealing extension plate projecting from one edge; of an auxiliary seal member removably engaged through said opening and having a portion resting upon the upper face of said body plate, said sealing extension plate being bent back over said body plate and a portion of said auxiliary seal member resting upon the same and secured to the opposite edge of said body plate.

In testimony whereof we affix our signatures in presence of two witnesses.

ARTHUR J. HODGE.
HENRY B. RUGGLES.
